TRAFFIC MARKER AND INDICUM

John N. Bensen, Brooklyn, N. Y.

Application September 23, 1937, Serial No. 165,272

5 Claims. (Cl. 94—1.5)

The invention relates to markers or indicia, such as letters, symbols, pointers, indicators and the like for the direction of traffic and other purposes and to the manner of applying them to a pavement. Lines, letters and symbols, for the direction of traffic, are generally made by painting them directly on the pavement and in some cases by inserting them in the pavement, either in the form of concrete or similar inlays, or by 10 glass or metal parts imbedded in the pavement.

The object of the present invention is to provide markers which are completely finished before being placed on the pavement and which may be made in any desired shape or length so as to produce any one of the numerous lines, numbers, 15 figures or other symbols now used for the direction of traffic. Another object is to so construct the markers that when once secured on the pavement there will be no danger of them becoming 20 loose or displaced.

A further object is to produce markers of this type which, even in the heaviest traffic, will last for a very long time and maintain the color imparted to them until completely worn away. A 25 still further object is to provide markers of this type which will be so flexible that they may be rolled, when made in large lengths, to facilitate their transportation and so that they may be shaped to assume the various curves encountered 30 on highways.

Additional objects are to produce markers which may be made of any desired color, which can be stored over a long period of time without losing their flexibility, which are easy to apply to 35 the pavement, and which can be manufactured in all kinds of shapes at a relatively low cost.

These and various other objects and advantages will be readily understood from the following 40 description and from the accompanying drawing of preferred embodiments of the invention, in which, however, various modifications may be made without departing from the scope of the appended claims. In the drawing,

Fig. 1 shows a plan view of a stop signal marker 45 made in accordance with the invention;

Fig. 2 is a plan view of another kind of marker;

Fig. 3 is a cross-sectional side view of Fig. 2;

Fig. 4 shows a marker such as is commonly used 50 for dividing the traffic on a highway; and

Fig. 5 shows a cross-sectional side view of a mould and illustrates one of the ways in which the markers, constituting the present invention, may be made.

55 In Fig. 5 a mould is shown at 10. A concave

depression is made in this mould and in this depression a piece of material to which paint will not readily adhere is preferably placed. I have found that "Cellophane" is particularly well suited for this purpose. After the Cellophane has been placed in the depression of the mould, a heavy 5 coat of any suitable paint is applied, as shown at 11. Next a layer of sharp sand, or other similar material, is distributed over the wet paint, as shown at 12. This sand will adhere to and mix 10 with the paint. After the paint is partly dried the loose sand, or such particles which have not adhered to the paint, are preferably removed in any suitable manner, as by inverting the mould or by blowing. Next another heavy coat of paint 15 13 is applied on top of the first coat of sand and on top of this paint another layer of sand 14 is placed, and so on, in alternate layers, until the mould is filled.

It is evident that the sand and the paint will 20 become so intimately mixed that the whole mass will assume the color of the paint used and form a homogeneous mass. Inasmuch as the final layer is sand, the upper part of the marker, as shown in the mould, will consist of a very rough 25 surface. This is the surface which is applied against the pavement as will be explained later. After the paint in the marker is sufficiently dry the marker is removed from the mould and may now be kept for any length of time until used. 30 It will be found, that when constructed in this manner, the marker will have great wearing qualities and be quite flexible so that it may be rolled or bent quite freely. The Cellophane may be removed from the marker at any time after 35 it is removed from the mould.

In Fig. 1, a marker, such as is generally shown at a crossing, is shown. In this particular instance it is made up of two straight strips 15 and a semi-circular piece 16, but these parts might 40 also be made in one piece. The letters 17 forming the word "Stop" are also made in a suitable mould, in the manner just described. In Fig. 2 a ring 18 is illustrated. This ring is used for the location of a signal device or the like. 45

Fig. 4 shows the manner in which the markers are used for dividing a highway into lanes. In this instance the line is made up of several separated parts 19, one of which is arcuated, as shown, at 19A, to indicate the manner in which 50 the markers can be bent. While this particular marker has been shown as made up of relatively short sections, it will be understood that the markers can be made up in strips of considerable length. 55

While the depression in the mould has been shown considerably deeper than would ordinarily be the practice, this has been done to more readily illustrate the idea. In practice a marker 5 about 3" wide would be only approximately $\frac{1}{8}$ " high. However, there are cases where it may be advantageous to make the markers considerably higher so that a driver would notice the wheels of a car going over them.

10 The markers are preferably applied to the pavement by hot pitch, which may either be applied to the marker itself or to the pavement. Inasmuch as the bottom of the marker is made up of sharp sand, it will be found that, after the 15 pitch cools, there is no danger of the marker working loose, even with heavy traffic. It will also be found that as the marker is gradually worn down its color will remain unchanged until completely worn away.

20 While I have shown certain kinds of markers it is, of course, evident that a great many others may be made. It will also be understood that, while I have shown a certain method for making the markers, I do not wish to confine myself to 25 this particular method as many other methods may be used. However, I find that by building the markers up in alternate layers, as explained, exceptional good results are obtained. The sand in the markers prevents the wheels of a car from 30 skidding, when passing over them.

Having described the invention and its objects, what I claim as new and wish to protect by Letters Patent is:

35 1. A portable bendable traffic marker for roadways having in cross-section a flat surface and a convex surface bounding a laminated structure of alternate layers of sand and paint.

2. A portable bendable traffic marker for roadways having in cross-section a flat surface and a convex surface bounding a laminated structure of alternate layers of sand and paint, the layer forming the convex surface comprising mostly 5 paint and the layer forming the flat surface comprising mostly sand.

3. A portable bendable traffic marker for roadways having in cross-section a flat surface and a convex surface bounding a laminated structure 10 of alternate layers of sand and paint, the layer forming the convex surface comprising mostly paint and the layer forming the flat surface comprising mostly sand, the layers of sand and paint being successively narrower from the center of 15 the convex surface to the flat surface.

4. A portable bendable traffic marker for roadways having in cross-section a flat surface and a convex surface bounding a laminated structure of alternate layers of sand and linseed oil 20 paint, the layer forming the convex surface comprising mostly paint and the layer forming the flat surface comprising mostly sand, the layers of sand and paint being successively narrower from the center of the convex surface to 25 the flat surface.

5. A portable bendable traffic marker for roadways having in cross-section a flat surface and a convex surface bounding a laminated structure of alternate layers of sand and linseed oil paint, 30 the latter forming the convex surface comprising mostly paint and the latter forming the flat surface comprising mostly sand, the layers of sand and paint being successively narrower from the center of the convex surface to the flat surface, 35 the paint being colored.

JOHN N. BENSEN.
